CLAIM

The ornamental design for a clamshell retail package for transponder, as shown and described.

DESCRIPTION

FIG. 1 is a front top left perspective view of a clamshell retail package for transponder, showing our new design;

FIG. 2 is a front bottom right perspective view thereof;

FIG. 3 is a rear bottom right perspective view thereof;

FIG. 4 is a left side view thereof, the right side view being a mirror image;

FIG. 5 is a front view thereof;

FIG. 6 is a back view thereof;

FIG. 7 is a top view thereof; and,

FIG. 8 is a bottom view thereof.

The broken line showing of a clamshell retail package for transponder is for illustrative purposes only and forms no part of the claimed design.
